UNITED STATES PATENT OFFICE.

JOE CRITES, OF EVANSTON, ILLINOIS, AND BERTRAM J. CROSS, OF GLENWOOD SPRINGS, COLORADO, ASSIGNEES TO INTERNATIONAL COMBUSTION ENGINEERING CORPORATION, OF NEW YORK, N. Y., A CORPORATION OF DELAWARE.

TRANSPORTATION AND DISTRIBUTION OF PULVERIZED MATERIAL PNEUMATICALLY.

Application filed October 11, 1924. Serial No. 743,123.

To all whom it may concern:

Be it known that we, JOE CRITES and BERTRAM J. Cross, citizens of the United States, residing at Evanston, in the county ⁵ of Cook and State of Illinois, and Glenwood Springs, county of Garfield and State of Colorado, respectively, have invented certain new and useful Improvements in Transportation and Distribution of Pulverized Material Pneumatically, of which the following is a specification.

Our invention relates to the transportation and distribution of pulverized material, powdered coal, for example, pneumatically, ¹⁵ and especially to a system for delivering the material in streams of equal density directly from the source to the burners or furnaces where the material is consumed.

One object of the invention is to provide ²⁰ an improved process and apparatus for subdividing a stream of this material suspended in air, in such a manner that each divisional stream will carry the same amount of solid material in proportion to the volume of air, per unit of time. Substantially the same device may be employed for re-establishing an even density of the solids throughout the cross-section of a single stream:

²⁵ In general, the material is forced from the pulverizer or other source of supply, in a single large stream through a main conduit. Each burner, furnace, or bin, is supplied through a separate supply conduit. These several points of delivery may be arranged separately or in groups, as desired. A system of distributors and branch conduits is arranged between the main conduit and the several supply conduits, the ³⁰ number, form and arrangement of these distributors depending upon the grouping of the installation to be served.

Each distributor is so formed as to subdivide the stream delivered thereto into a plurality of streams, each of which is drawn from substantially every portion of the cross-sectional area of the first stream, so that the density of all streams remains equal. We here disclose two types of distributors, one of which will divide the first stream into a pair of streams, and the other dividing the first stream into three streams. By a suitable combination of the required

number of distributors of these two types, any desired number of subdivisions may be ⁵⁵ obtained.

More specifically, each distributor comprises means for dividing the streams fed thereto, into a multiplicity of similar small streams, and then distributing these numerous small streams among the two or more branch streams, in such a manner that the material delivered to the branches is drawn from all portions of the main stream. For example, to supply two branch streams, each ⁶⁵ alternate sub-division of the main stream is directed into one of the two branches. For three branch streams, every third one of the subdivisions is directed into one of the branch streams. In this way, if any ⁷⁰ portion of the main stream is denser than other portions, by dividing this denser portion equally between the several branches, the density of the branches will be equalized. ⁷⁵

By using such distributors at every point where a stream of the material is divided or split into two or more branches, the density of the mixture will be maintained equal in every branch, and at every point of delivery or consumption. ⁸⁰

Also by placing one of these distributors at any intermediate point in a long pipe line, the several divisions of the material being fed back into the pipe, it will act as ⁸⁵ a reconditioner to reestablish an even density of the material throughout the cross-section of the pipe or conduit.

The above, and other objects and advantages of this invention will be apparent ⁹⁰ from the following detailed description of certain approved forms of apparatus suitable for carrying out the principles of this invention.

In the accompanying drawings:

Fig. 1 is a general diagrammatic view of one transporting and distributing system.

Fig. 2 is a similar view of another system, involving the use of reconditioners.

Fig. 3 is an end view, partially broken ¹⁰⁰ away, of one of the two-way distributors.

Fig. 4 is a side view, partially broken away, of this distributor. This view is taken looking from the left at Fig. 3.

Fig. 5 is a horizontal section, taken substantially on the line 5—5 of Fig. 4. ¹⁰⁵

Fig. 6 is a perspective view of one of the deflecting plates.

Fig. 7 is a perspective view of one of the dividing plates.

5 Fig. 8 is an end view, similar to Fig. 3, showing a three-way distributor.

Fig. 9 is a side view of the distributor shown in Fig. 8, looking from the left at Fig. 8.

10 Fig. 10 is a horizontal section, taken substantially on the line 10-10 of Fig. 8.

Fig. 11 is a perspective view of one of the built-up deflecting units.

15 Fig. 12 is a perspective view of one of the division plates, used between the units shown in Fig. 11.

Fig. 13 is a side elevation, showing one of the two-way distributors used as a re-conditioner in a single pipe line.

20 Fig. 14 is an elevation of the reconditioner looking from the left of Fig. 13.

Fig. 15 is a similar view, partially in section, showing a pair of these distributors used for this purpose.

25 Fig. 16 is a similar view looking from the left at Fig. 15.

Referring first briefly to Fig. 1, a pulverizer is indicated diagrammatically at 1, in which the material, coal, for example, is 30 reduced to a powdered state and then forced pneumatically, in suspension in air, through a main conduit 2. At 3, 4, and 5 are indicated furnaces, each individual burner of which is fed through a separate supply conduit 6. The main conduit 2 connects with the several supply conduits 6, through a series of distributors and branch conduits, the arrangement and number of which will vary for different installations, and before 35 proceeding further with the description of the general system we will describe in detail the improved distributor units used in this system.

Referring now to Figs. 3 to 7 inclusive, 40 which show a two-way distributor, 7 indicates the feed pipe or conduit leading thereto, and 8 and 9 the pair of branch conduits leading therefrom.

Where pulverized material is transported 45 in suspension in an air current through a conduit which has elbows, angles or curved portions, centrifugal force tends to bring about an unequal distribution of the solids in the stream, transversely thereof, and this 50 inequality in density tends to persist even after the stream has entered a straight section of the conduit. A similar condition of unequal density in different parts of the cross section of the stream may be brought 55 about through the action of gravity in any portion of the transporting conduit which is not vertical. If the stream of air and solids under conditions such as these is divided, half, for example, being sent to one 60 furnace or bin and the other half to another 65

furnace or bin, the ratio of solids to air volumes is likely to be quite different in the two streams, and this is objectionable for obvious reasons, especially in the case of pulverized fuel fed directly to furnaces. 70 The distributors here disclosed provide a remedy for this difficulty.

Upper portions of the branch conduits 8 and 9 are widened out, as shown in Fig. 4, and their outer and inner walls made flat 75 so that an angular ridge 10 is provided at the junction of the two branches, the branch pipes opening out of a common section 11 of the structure, which is preferably quite narrow in the plane of Fig. 3, and considerably broader in the plane of Fig. 4. This section 11 preferably has a long and narrow rectangular cross section, such as indicated in Fig. 5.

Interposed between the branch conduit 80 structure 11, just described, and main conduit 7 is a casing 12 in the form of a truncated pyramid having a circular flange portion 13 for connection with the conduit 7 and a rectangular flange portion 14 for connection with the upper end of the branch pipe structure 11. The stream of material entering casing 12 from conduit 7 is, therefore, narrowed in one direction and allowed to expand in the other direction, so that it 85 has the rectangular cross section indicated in Fig. 5. After entering the casing 11, this stream is divided transversely into a multiplicity of similar small streams by means of a number of dividing plates 15 and 16, and 90 deflecting plates 17 and 18, which are arranged in alternation in the space within structure 11 above the junction of branch conduits 8 and 9. The division plates 15 and 16 extend transversely of casing 11 in the direction of its narrower dimension. These so-called division plates 15 are flat plates 95 formed with notches 19 in their lower edges, so that the plates fit over the angular ridge 10 at the junction of branch conduits 8 and 9. The division plates 16 are triangular in shape, with their pointed ends 20 extending downwardly in line with and against the ridge 10, and the deflecting plates 17 and 18 are preferably formed integrally with division plate 16, as right-angle flanges extending from the downwardly converging sides of these division plates 16. The rectangular extensions 21 at the lower ends of the deflecting plates 17 and 18, are adapted 100 to seat upon the sides of ridge 10. The division plates 15 and 16 are arranged in alternation throughout the length of casing 11, and the width of the deflecting plates 17 and 18 determines the width of the passages 105 22 between the division plates. In the construction here shown, there are twelve of these vertical passages 22, six leading to conduit 8, and six to conduit 9, but it is to be 110 understood that this is merely illustrative, 115 120 125 130

and that any desired number of these passages might be used.

By this arrangement of the dividing and deflecting plates, the stream of air and solids, 5 entering the distributor from conduit 7 is divided into a multiplicity of smaller streams, and these streams are directed alternately into the branch conduits 8 and 9. Suppose that the stream passing down 10 through conduit 7 into the casing 12 is dense with solids on the right hand side of the conduit, as viewed in Fig. 4, and contains a much smaller proportion of solids on the left hand side thereof. This denser mixture 15 at the right hand side of the distributor, will be split up between the several passages 22 at this side of the device, and distributed in substantially equal proportions to the two branches 8 and 9. The same will be true of 20 the lighter material in the left hand side of the device. That is, the stream is first spread out, preferably, so that it is much wider in one direction than the other, and then is cut up into sections narrow enough, in 25 the direction of the greater width of the main stream, so that when these divided streams are sent alternately to the branch conduits, each branch stream will receive practically the same proportion of solids, no 30 matter how unequal may be the distribution of the solids in the cross section of the main stream. The result is that regardless of the inequality of distribution of the solids with respect to the cross-section of the main 35 stream, each of the branch streams will carry approximately the same amount of solids per unit volume of air.

As a matter of convenience, the casing 12 may be provided with an opening 23 for 40 clean out and repair purposes, the opening being normally covered by closure 24.

In the three-way distributor shown in Figs. 8 to 12 inclusive, the main conduit 7 and casing 12 are practically the same as in the form previously described. The three- 45 branch conduits 25, 26 and 27 are each flared out or made broader at its upper end, as indicated at 28, and the three conduits join with the lower portion of a casing 29, whose upper cross section, as indicated in 50 Fig. 10, is quite similar in conformation to the corresponding section of the casing 11 previously described. The junction of the flat portion of branch conduits 25 and 26 55 forms a ridge 30, and the junction of conduits 26 and 27 forms a ridge 31.

In this form of distributor, the dividing and deflecting members preferably comprise built-up units such as shown at 60 32 in Fig. 11 wherein the narrow rectangular open ended boxing 32 has end walls 33 and side walls 34, to which are secured the diagonally disposed deflecting plates 35 and 36. The width of end 65 plates 33 is substantially the same as that

of the deflecting plates 35 and 36, so that the width of the passage 37 through the boxing 32, will be substantially the same as that of the passages 38 formed between the side plates 34, deflector plates 35 and 36, and the 70 division plate 39, shown in Fig. 12, one of which is mounted between each adjacent pair of the units shown in Fig. 11. The width of plates 34 and 39 is substantially the same as the distance between ridges 30 and 75 31, and the lower ends of the deflecting plates 35 and 36 are adapted to connect with the ridges respectively.

It will be noted that each of the vertical 80 passages 37 connect with the branch conduit 26, whereas the deflecting passages 38 (of which there are twice as many as of the 85 passages 37), are directed alternately into the branch conduits 25 and 27. In this manner, each of the branch conduits 25, 26 or 27, 90 is fed from every third passage throughout the length of casing 29. By making these 95 passages 37 and 38 sufficiently narrow and numerous, substantially the same results are obtained, and in the same manner, with this 100 three-way distributor as with the two-way distributor previously described.

With slight structural changes, one or 105 more of these distributors can be used to recondition, or render more homogeneous, a 95 stream of material which has travelled for some distance through a single conduit. As shown in Figs. 13 and 14, a single two-way distributor 40 is positioned at some intermediate point in the pipe line or conduit 41, 100 the branch conduits 42 and 43 leading from the distributor 40 being directed back into the continuation of the conduit 41. It will be noted that the branch pipes 42 and 43 are twisted relatively through about 90° 105 to avoid returning the material to the same portions of pipe 41 previously occupied by it.

A more efficient device of this type is shown in Figs. 15 and 16, in which a pair 110 of two-way distributors 44 and 45 are positioned successively in the conduit at right angles to one another, so that the material 115 will be successively split up in two different directions substantially at right angles to one another. In this form, the two branch pipes 42 and 43 may be omitted, and the lower portion of the casing below the dividing walls, may be divided at right angles 120 to these walls into two halves by means of a vertical partition 46. The spaces at the two sides of wall 46 correspond to the branch conduits 42 and 43 in Figs. 13 and 14. Obviously a three-way distributor might be 125 adapted to either form of reconditioner, above described.

Referring now again to the installation indicated diagrammatically in Fig. 1, the main conduit 2 is shown connecting with a three-way distributor A, which supplies the three 130

branch conduits 47, 48 and 49. The branch conduit 47 leads to a two-way distributor B, which immediately feeds a pair of two-way distributors C and D, from the branches of which lead the four supply pipes 6 for the burners of furnace 3. As illustrating a slightly different construction, the branch conduit 48 is shown connecting with a two-way distributor E from which lead the branch conduits 50 and 51. 50 is shown leading to a two-way distributor F, positioned near the furnace, which distributor feeds the two conduits 6 supplying two of the burners of furnace 4. In the same manner, branch conduit 51, through distributor G, supplies the other two conduits 6 for the other pair of burners of furnace 4. The furnace 5 is illustrated as having three burners, the supply conduits 6 of which are fed from a three-way distributor H connected with the third main branch conduit 49.

In another typical installation, indicated in Fig. 2, the pulverizer 1 supplies powdered fuel to the burners of furnaces 3, 4 and 5, through distributors A to H inclusive, and branch conduits 47 to 51, as in Fig. 1. In this installation, conduit 2 being of considerable length, a reconditioner M, of the type shown in Figs. 13 and 14 is positioned in this conduit at an intermediate point to reestablish a more uniformly dense flow of the material through the conduit. In the same manner, branch conduit 47 being of considerable length, a reconditioner N, this time of the type shown in Figs. 15 and 16 is placed at a suitable intermediate point in the run of pipe or conduit 47. Obviously the type of reconditioners shown at M and N could be interchanged or both might be of the same type.

Of course, the above described sample installations, are only examples of countless combinations that might be arranged. In every case, however, the density of the mixture of air and solids in each one of the conduits will remain the same as that in the main conduit, and in all of the other conduits, despite the fact that the mixture in any one or all of the conduits may not always be homogeneous throughout the cross-sectional area of that conduit.

While in the distributors illustrated, the branch conduits leading from each distributor here shown are of equal size and volume, it is obvious that by suitably varying the size of the sub-divisions in the distributor, branch conduits of unequal size may be supplied therefrom. For example, if one branch conduit of a two-way distributor has twice the volume of the other, the distributor would be formed with every alternate passage twice as large as those adjacent thereto. Similar results could be obtained by arranging the deflector plates in the

passages, so as to divert a larger number thereof, at properly spaced intervals, to the larger branch conduit.

We claim:

1. In combination with a conduit for transportation of pulverulent material pneumatically, and a plurality of branch conduits, means for dividing the stream of air and suspended solids passing through the main conduit into a greater number of streams than the number of branch conduits and then directing certain of these streams into each branch conduit. 70

2. In combination with a conduit for transportation of pulverulent material pneumatically, means for dividing the stream of air and suspended solids passing through the conduit into a plurality of streams and deflecting each alternate stream in one direction and the other streams in another direction. 80

3. In combination with a conduit for transportation of pulverulent material pneumatically, means for dividing the stream of air and suspended solids passing through the conduit into a plurality of streams and deflecting the divided streams angularly from the main stream in alternation, one set of alternate streams from one side of the main stream and the other set from the other side. 90

4. In combination with a conduit for transportation of pulverulent material pneumatically, means for dividing the stream of air and suspended solids passing through the conduit into a series of parallel streams; and a plurality of branch conduits, the divided streams from the main conduit being fed into the branch conduits in successive order throughout the series. 100

5. In combination with a conduit for transportation of pulverulent material pneumatically, a portion of which is wider in one direction than in the other, means in said portion of the conduit for dividing the stream across its narrower dimension into a plurality of streams, and for deflecting said divided streams angularly from the main stream in alternation, one set of alternate streams to one side, with respect to the greater cross-sectional area of the main stream and the other set to the other side. 110

6. In combination with a conduit for transportation of pulverulent material pneumatically, a portion of which is wider in one direction than in the other, means in said portion of the conduit for dividing the stream across its narrowed dimension into a plurality of streams, and for deflecting said divided streams angularly from the main stream in series to form a plurality of branch streams. 120

7. In combination with a main conduit for transportation of pulverized material pneumatically, branch conduits leading from the main conduit, and means located 130

- at the junction of the main and branch conduits for dividing the main stream of air and solids and deflecting the divided streams to the branch conduits so that the ratio of 5 solids to air in the branch conduits is approximately uniform regardless of differences in density of the mixture in different portions of the cross-section of the main stream.
- 10 8. In combination with a main conduit for transportation of pulverulent material pneumatically, branch conduits leading from the main conduit, and means located at the junction of the main and branch conduits for dividing the main stream of air and solids into a series of smaller streams and deflecting these streams into the branch conduits, the streams deflected into any one branch conduit being selected at regularly 15 spaced intervals throughout the series.
- 15 9. In combination with a main conduit for transportation of pulverulent material pneumatically, branch conduits leading from the main conduit, and means located at the junction of the main and branch conduits for splitting the main stream into a series of substantially parallel streams, and deflecting these latter streams into the branch conduits, the streams deflected into any one 20 branch conduit being selected at regularly spaced intervals throughout the series.
- 20 10. In combination with a main conduit for transportation of pulverulent material pneumatically, a portion of which is wider in one direction than in the other, branch 25 conduits leading from said portion, and means in said portion for dividing the stream of air and solids across its narrower dimension into a series of smaller streams and for deflecting said divided streams into the branch conduits, the streams deflected into any one branch conduit being selected at regularly 30 spaced intervals throughout the series.
- 30 11. In combination with a main conduit for transportation of pulverulent material pneumatically, a portion of which is wider in one direction than in the other, branch 35 conduits leading from the wider sides of this portion, and means in the aforesaid portion of the main conduit for dividing the stream of air and solids across its narrower dimension into a series of smaller streams and for deflecting said divided streams to 40 said branch conduits, the streams deflected into any one branch conduit being selected at regularly spaced intervals throughout the series.
- 45 12. In combination with a main conduit for transportation of pulverulent material pneumatically, a portion of which is wider in one direction than in the other, branch 50 conduits leading from said portions, one from each of its wider sides, means in said portion of the main conduit for dividing 55 the stream across its narrower dimension into a plurality of streams, and deflecting said streams in alternation, one set of alternate streams into one of the branch conduits and the other set into the other branch 60 conduit.
- 60 13. In combination with a main conduit for transportation of pulverulent material pneumatically, a portion of which is wider in one direction than in the other, branch 65 conduits leading from this portion of the main conduit, one from each of its wider sides, and a plurality of plates in this portion of the conduit extending in the direction of the narrower dimension thereof, and means arranged between said plates for deflecting the streams of air and solids into said branch conduits alternately.
- 70 14. In combination with a main conduit for transportation of pulverulent material 75 pneumatically, a portion of which is wider in one direction than in the other, a plurality of plates in this portion of the conduit extending in the direction of the narrower dimensions thereof, and means between said plates for deflecting the divided streams alternately to opposite sides of said conduit.
- 75 15. In combination with a main conduit for transportation of pulverulent material 80 pneumatically, a plurality of plates in said conduit and means between said plates for deflecting the streams of air and solids between the plates alternately to opposite sides of said conduit.
- 80 16. In combination with a conduit for transportation of pulverulent material pneumatically, a pair of branch conduits diverging therefrom and providing an angular ridge between them, a plurality of dividing and deflecting plates in the main conduit, the ends of which fit over said ridge and which are formed to divide the stream of air and solids and deflect the divided streams into said branch conduits alternately.
- 85 17. In combination with a conduit for transportation of pulverulent material pneumatically, a pair of branch conduits diverging therefrom and providing an angular ridge between them, a plurality of dividing plates in the main conduit, the ends of which are notched to fit over said ridge, and a plurality of deflecting plates between 90 said dividing plates having oppositely sloping flanges on opposite sides to deflect streams of air and solids into the branch conduits alternately.
- 90 18. In combination with a conduit for transportation of pulverulent material 95 pneumatically, a portion of which is wider in one direction than the other, a pair of branch conduits diverging from the main conduit at the wider sides thereof, a plurality of dividing plates in the aforesaid 100
- 100 110
- 105 115
- 110 120
- 115 125
- 120 130

portion of the main conduit extending across the same in the direction of the narrower dimension, and a plurality of deflecting plates between said dividing plates having oppositely inclined flanges on opposite sides to deflect streams of air and solids into said branch conduits alternately.

19. In combination with a conduit for transportation of pulverulent material pneumatically, a portion of which is wider in one direction than the other, a pair of branch conduits diverging from the main conduit at the wider sides thereof, and a third branch conduit substantially in line with the main conduit and between the two side branch conduits, a plurality of dividing plates in the aforesaid portion of the main conduit extending across the same in the direction of the narrower dimension and forming a plurality of similar separate passages, these passages comprising three distinct series, each third passage belonging to the same series, a deflector plate in each passage of one series to deflect the suspended material into one side branch conduit, an oppositely disposed deflector plate in each passage of the second series to deflect the material in the passages into the other side branch conduit, and a pair of parallel plates enclosing the other sides of each passage of the third series whereby the material therein is directed into the central branch conduit.

20. In combination with a main conduit for transportation of pulverulent material pneumatically, a portion of which has a rectangular cross-section, a plurality of substantially parallel plates in said rectangular portion extending across the conduit in the direction of the narrower dimension thereof and forming a series of passages amongst which the stream of material in the main conduit is divided, a plurality of branch conduits, and deflector plates in the passages for directing the material therein into some one of the branch conduits.

21. In combination with a main conduit for transportation of pulverulent material pneumatically, a portion of which has a rectangular cross-section, a plurality of substantially parallel plates in said rectangular portion extending across the conduit in the direction of the narrower dimension thereof and forming a series of passages amongst which the stream of material in the main conduit is divided, a plurality of branch conduits, the passages being divided into as many series as there are branch conduits, the passages of each series being separated by passages of the other series, and similar deflecting means associated with each passage of any one series for directing the material in each of these passages into a certain branch conduit.

22. In combination with a main conduit

for transportation of pulverulent material pneumatically, a portion of which has a rectangular cross-section, a plurality of substantially parallel plates in said rectangular portion extending across the conduit in the direction of the narrower dimension thereof and forming a series of passages amongst which the stream of material in the main conduit is divided, and means associated with the passages for directing the material in successive passages in different directions.

23. The method of subdividing a flowing stream of pulverized material suspended in air, consisting in splitting the main stream into a series of similar parallel streams and then deflecting and combining alternate streams of the series to form one of the subdivisions of the main stream.

24. The method of subdividing a flowing stream of pulverized material suspended in air, consisting in splitting the main stream into a series of similar parallel streams, certain of these subsidiary streams being deflected and combined to form one of the subdivisions of the main stream, the subsidiary streams of any one set being taken at spaced intervals from end to end of the series into which the main stream is split.

25. The method of subdividing a flowing stream of pulverized material suspended in air, consisting in causing the main stream to assume a relatively broad and narrow form, splitting this portion of the stream at right angles to its broader dimension into a series of similar parallel streams, and then combining streams selected from spaced points throughout the series to form one of the subdivisions of the main stream.

26. The process which consists in pulverizing fuel, forcing a stream of the fuel suspended in air through a suitable conduit, splitting the stream into a multiplicity of similar subdivisions, selectively combining certain of the subdivisions to form an auxiliary stream, and delivering this auxiliary stream to a burner.

27. The process which consists in pulverizing fuel, forcing a stream of the fuel suspended in air through a suitable conduit, splitting the stream into a multiplicity of similar subdivisions, selectively combining certain of the subdivisions to form an auxiliary stream, splitting this auxiliary stream into a multiplicity of subdivisions, and selectively combining certain of these latter subdivisions to form a supply stream which is delivered to a burner.

28. In a system of the character described, a source of pulverized material suspended in air, a main conduit leading therefrom, a plurality of burners, a separate supply conduit leading to each burner, and a combination of distributors and branch conduits between the main conduit and the supply conduits, each distributor comprising means for se-

lecting the material delivered to each branch conduit from substantially all portions of the stream delivered to the distributor whereby a mixture of the same density will be furnished to each of the supply conduits.

29. In a system of the character described, a source of pulverized material suspended in air, a main conduit leading therefrom, a plurality of burners, a separate supply conduit leading to each burner, and a combination of distributors and branch conduits between the main conduit and the supply conduits, each distributor comprising means for selecting the material delivered to each branch conduit from substantially all portions of the stream delivered to the distributor whereby the mixture of material and air delivered to each supply conduit will be selected from all portions of the original stream in the main conduit.

30. In combination with a conduit for transportation of pulverulent material pneumatically, and a plurality of branch conduits, means for dividing the stream of air and suspended solids passing through the main conduit, into a greater number of streams than the number of branch conduits and then directing certain of these streams selected from spaced portions of the main stream, into each branch conduit.

31. In a system of the character described, a source of pulverized material suspended in air, a conduit leading therefrom, a plurality of branch conduits, and a distributor connecting the main conduit with the branch conduits, the distributor including means for selecting the material delivered to each branch conduit from substantially all portions of the stream in the main conduit.

32. In a system of the character described, a source of pulverized material suspended in air, a conduit leading therefrom, a plurality of branch conduits, and a distributor connecting the main conduit with the branch conduits, the distributor comprising a multiplicity of subdivisions connected in interspaced order with the branch conduits, whereby each branch is fed equally from substantially all portions of the main stream.

33. In a system of the character described, a source of pulverized material suspended in air, a conduit leading therefrom, a plurality of branch conduits, and a stationary distributing device connected with the main conduit and the branch conduits and comprising means for dividing all portions of the main stream substantially equally between the several branches.

34. In a system of the character described, a source of pulverized material suspended in air, a distributor, a conduit leading from the source to the distributor, a plurality of branch conduits leading from the distributor, a plurality of distributors each fed by

one of the branch conduits, and subsidiary branch conduits leading from each distributor, each distributor comprising means for dividing substantially all portions of the stream flowing therewith equally between the conduits leading therefrom.

35. In a system of the character described, a source of pulverized material suspended in air, a distributor, a conduit leading from the source to the distributor, a plurality of branch conduits leading from the distributor, a plurality of distributors each fed by one of the branch conduits, and subsidiary branch conduits leading from each distributor, each distributor comprising a multiplicity of subdivisions connected in interspaced order with the branch conduits leading therefrom.

36. In combination with a conduit for the transportation of pulverulent material pneumatically, means for redistributing the suspended solids in the stream of air passing through the conduit so as to make the stream more uniformly dense throughout the cross-sectional area of the conduit, comprising a plurality of division plates for dividing the main stream into a multiplicity of branches, and means for collecting the branch streams and returning them to the conduit in a rearranged order.

37. The method of redistributing the suspended solids in the stream of air passing through a conduit, consisting in separating the stream into a multiplicity of divisions, and then returning these divisions to the conduit in a rearranged order.

38. In a system of the character described, a source of pulverized material suspended in air, a plurality of burners, a system of conduits and distributors for conducting the material from the source to the burners, and a device mounted in one of the conduits for redistributing the mixture flowing therethrough so that a substantially uniform density of the mixture is obtained throughout the cross-sectional area of the conduit, said device comprising means for separating the stream into a multiplicity of divisions, and then returning these divisions to the conduit in a rearranged order.

39. In a system of the character described, a source of pulverized material suspended in air, a burner, a conduit for conveying the material from the source to the burner, and a device mounted at an intermediate position in the conduit for redistributing the mixture flowing therethrough so that a substantially uniform density of the mixture is obtained throughout the cross-sectional area of the conduit, said device comprising means for separating the stream into a multiplicity of divisions, and then returning these divisions to the conduit in a rearranged order.
